CLAIM

The ornamental design for: base for elevating a toilet, as shown and described.

DESCRIPTION

FIG. 1 is a bottom side perspective view showing my new design for a base for elevating a toilet;

FIG. 2 is a bottom plan view shown on a reduced scale thereof;

FIG. 3 is a front elevation view shown on a reduced scale thereof, the rear elevation view being identical;

FIG. 4 is a left side elevation view shown on a reduced scale thereof, the right side elevation view being identical;

FIG. 5 is a top plan view shown on a reduced scale thereof; and,

FIG. 6 is a cross sectional view shown on a reduced scale taken along line 6—6 shown in FIG. 2.
